(57) **CLAIM**

The ornamental design for a dispenser, as shown and described.

DESCRIPTION

FIG. 1 is a front and right perspective view of a dispenser showing my new design;

FIG. 2 is a front elevational view of the dispenser of FIG. 1; FIG. 3 is a back elevational view of the dispenser of FIG. 1; FIG. 4 is a left side elevational view of the dispenser of FIG. 1;

FIG. 5 is a top plan view of the dispenser of FIG. 1; and,

FIG. 6 is a bottom plan view of the dispenser of FIG. 1.

The dotted lines are included for the purpose of illustrating portions of the dispenser that form no part of the claimed design, with the dot-dot-dash lines being representative of the unclaimed lower boundary of the design.
